UNITED STATES PATENT OFFICE.

CLARENCE DALE VEST, OF MARTINEZ, CALIFORNIA, ASSIGNOR OF ONE-HALF TO
FREDERICK A. YOUNG, OF MARTINEZ, CALIFORNIA.

ELECTRIC CONTROLLER.

1,215,592.

Specification of Letters Patent. Patented Feb. 13, 1917.

Application filed July 17, 1915. Serial No. 40,492.

To all whom it may concern:

Be it known that I, CLARENCE DALE VEST, a citizen of the United States, and a resident of Martinez, Contra Costa county, State of California, have invented a certain new and useful Electric Controller, of which the following is a specification:

The invention relates to time controlled devices for opening and closing electric circuits.

An object of the invention is to provide a time controlled device of simple construction for opening and closing electric circuits.

Another object of the invention is to provide a time controlled device for opening and closing electric circuits by means of which the periods of duration of the closed circuit may be varied.

Another object of the invention is to provide a clock having means for alternately opening and closing an electric circuit.

The invention possesses other advantageous features, some of which, with the foregoing, will be set forth at length in the following description, where I shall outline in full that form of the invention which I have selected for illustration in the drawings accompanying and forming part of the present specification. In the drawings I have shown only one embodiment of my invention, but it is to be understood that I do not limit myself to such form, since the invention may be embodied in other forms.

Referring to said drawings:

Figure 1 is a front view of one embodiment of the controller of my invention.

Fig. 2 is a top view of the controller showing the electric circuit, part of the figure being a section taken on the line A—A

Fig. 1.

Fig. 3 is a section taken on the line C—C

Fig. 1.

Fig. 4 is a section taken on the line B—B

Fig. 2.

The controller of my invention is particularly adapted to be used in connection with electric heating devices, for opening the electric circuit so that the temperature of the device does not become excessive. The temperature of some heating devices, such as electric blankets, increases in time with the duration of the current and after a certain duration the temperature becomes excessive and dangerous. In accordance with my invention I provide means whereby

the electric circuit is alternately opened and closed, the duration of the closed and open periods being such that the device becomes heated, but not over-heated. During the closed circuit periods the temperature increases and during the open circuit period the temperature decreases, and the duration of the open and closed periods is such that overheating does not occur. For any particular heating device these periods may be predetermined and when the controller is to be used only in connection with a given heating device, the controller may be made so that these periods are fixed. When it is to be used on different heating devices, or when different maximum temperatures of a given device are desirable, the controller is made so that the duration of the periods may be varied. While I have specifically mentioned electric blankets, it is to be understood that the controller is in no manner limited in its use to electric blankets, but may be employed in connection with any heating device, the maximum temperature of which it is desirable to control.

The controller comprises a clock mechanism inclosed in a suitable case 2. The clock dial 3 is made of insulating material and contacts are arranged in or on the dial. The dial is provided with the usual numerals 4 as is the ordinary clock dial. Arranged in front of the clock dial is a minute hand 5 made of insulating material. Embedded in the dial is a metallic ring 6, concentric with the shaft 7 on which the hand is mounted. The ring 6 is provided with spaced segmental projections 8 which extend through the dial and preferably lie flush with the front face of the dial. These projections form one set of contacts through which the circuit is closed.

Arranged concentrically with and spaced from the ring 6 is a metallic ring 9 which is also secured to the dial. The ring 9 is connected to the source of power by the wire 12 and the ring 6 is connected to the other side of the power source through the heating device 14 by the wire 15.

Mounted on the hand 5 is an electric conductor which operates to close the circuit between the contacts 8 and the ring 9 as the hand revolves. In the present instance this conductor consists of a pair of brushes 17—18, connected together, the brushes being arranged to engage the ring 9 and the

2 contacts 8, and thereby close and open the electric circuit. When fixed periods of open and closed circuits are desired, the ring 9 may be exposed on the surface of the dial 5 for its entire periphery and the brush 17 may be in continual engagement with the ring, the circuit being opened and closed by the brush 18 passing from or into contact with the contacts 8.

10 When it is desirable, however, to vary the periods of duration of open and closed circuits the ring 9 is rotatably mounted on the dial and its surface is divided into spaced contact segments 19 by segments of 15 insulation 21. The ring 9 is preferably formed in parts consisting of the continuous base ring 22 and the contacts 19 and the insulator segments 21 screwed thereto. The parts are flanged so that the ring, while 20 rotatable, is held to the dial. Secured to one of the segments are means, such as a pointer 23, by which the ring may be rotated. The segments 19 and 8 preferably span the same arc so that they may be completely aligned radially and when they are 25 arranged in this position, the duration of the closed circuit is at a maximum. When the period of closed circuit is to be shortened and the period of open circuit lengthened, the ring 9 is rotated slightly to stagger or partly stagger the contacts 19 and 8 and the circuit is closed during the travel of the brushes over those portions of the contacts which are radially aligned. If the angle 30 of the contact segments is equal to the angle of the insulated gap between the segments, the segments may be adjusted relatively so that the circuit will be closed dur-

ing the length of time required by the hand to travel through such angle or the segments may be completely staggered, so that the circuit remains continually open. Any adjustment between these extremes may be had.

In accordance with this construction, the 45 clock mechanism operates to alternately open and close the electric circuit by connecting two insulated contacts and the current passes through the contacts only and not through the clock mechanism. 50

I claim:

1. An electric controller comprising a dial of insulating material, a hand overlying said dial, clock mechanism for rotating said hand, a series of contacts on said dial 55 arranged concentrically with respect to the center of rotation of said hand, a second series of contacts arranged concentrically with respect to said first named series and movable circularly with relation thereto, an 60 open electric circuit connected to said two series of contacts and means on the hand adapted to close said circuit.

2. An electric controller comprising a circularly arranged series of segmental contacts, a second series of segmental contacts arranged concentrically with and movable circularly with respect to said first series, an 65 open electric circuit connected to said two series and a concentrically movable conductor adapted to open and close the circuit between said two series of contacts. 70

In testimony whereof, I have hereunto set my hand at Martinez, California, this 29th day of June, 1915.

C. DALE VEST.
